Primary Examiner — Robert M Spear*Assistant Examiner* — Eliza Bennett-Hattan(74) *Attorney, Agent, or Firm* — Pearne & Gordon LLP(57) **CLAIM**

The ornamental design for a wire coil package, as shown and described.

DESCRIPTION

FIG. 1 is a top perspective view of wire coil package showing my new design with environment shown in broken lines;

FIG. 2 is a bottom perspective view thereof;

FIG. 3 is a front view thereof;

FIG. 4 is a rear view thereof;

FIG. 5 is a top view thereof with the bottom view being a mirror image thereof; and,

FIG. 6 is a left side view thereof with the right side being a mirror image thereof.

The broken lines shown are environmental only and form no part of the claimed design.

1 Claim, 4 Drawing Sheets(56)
